DESIGN FOR A HAND CARRIER FOR PARCELS

Doris Sophie Munn, Wolverhampton, England

Application December 17, 1935, Serial No. 60,137

Term of patent 7 years

To all whom it may concern:

Be it known that I, Doris Sophie Munn, a British subject, residing at Wolverhampton, England, have invented a new, original, and ornamental Design for a Hand Carrier for Parcels, of which the following is a specification, reference being had to the accompanying drawing, forming part thereof, which is a perspective view of the hand carrier for parcels showing my design.

I claim:

The ornamental design for a hand carrier for parcels, as shown.

DORIS SOPHIE MUNN.
